(57) **CLAIM**

The ornamental design for a fuel injection pipe, as shown and described.

DESCRIPTION

FIG. 1 is a perspective view of a fuel injection pipe showing our new design;

FIG. 2 is a front view thereof, the rear view being a mirror image;

FIG. 3 is a right side view thereof, the left side being a mirror image;

FIG. 4 is a top plan view thereof;

FIG. 5 is a bottom view thereof;

FIG. 6 is a cross-sectional view taken along line 6-6 in FIG. 3;

FIG. 7 is another perspective view showing an alternate position with the interior element pulled out; and,

FIG. 8 is a perspective view showing a fuel injection pipe of the present invention in an environment in which it may be used.

In FIG. 8, the broken lines depict environmental subject matter only that forms no part of the claimed design.
